(74) Attorney, Agent, or Firm — Sheppard, Mullin,
Richter & Hampton LLP(57) **CLAIM**

We claim the ornamental design for a flashlight, as shown and described.

DESCRIPTION

FIG. 1 is a top, front and left side perspective view of an ornamental design for a flashlight;

FIG. 2 is a front elevational view thereof;

FIG. 3 is a back elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken lines illustrate portions of the flashlight that form no part of the claimed design.
